UNITED STATES PATENT OFFICE.

GOODRICH Q. LEWIS, OF WHEATON, ILLINOIS, ASSIGNOR TO WILLIAM H. MINER, OF CHAZY, NEW YORK.

DRAFT-RIGGING.

1,283,536.

Specification of Letters Patent.

Patented Nov. 5, 1918.

Application filed February 26, 1917. Serial No. 150,963.

To all whom it may concern:

Be it known that I, GOODRICH Q. LEWIS, a citizen of the United States, residing at Wheaton, in the county of DuPage and State 5 of Illinois, have invented a certain new and useful Improvement in Draft-Rigging, of which the following is a full, clear, concise, and exact description, reference being had to the accompanying drawings, forming a 10 part of this specification.

This invention relates to improvements in draft riggings.

One object of the invention is to provide a draft rigging for railway cars wherein a 15 spring gear of high capacity is employed in combination with a novel two-part horizontal yoke detachably connected with the draw bar.

Another and more specific object of the invention is to provide a novel form of two-part horizontal yoke.

In the drawing forming a part of this specification, Figure 1 is a longitudinal section of a draft rigging of a car showing my 25 improvements in connection therewith. Fig. 2 is a horizontal sectional view of the structure illustrated in Fig. 1 and taken on the line 2—2 thereof. Fig. 3 is a vertical, transverse sectional view of the structure illustrated in Fig. 1 and taken on the line 3—3 thereof. And Fig. 4 is a perspective view of one of the stop castings employed with my improvements.

In said drawings, 10—10 denote channel 35 center or draft sills of a car underframe, to the inner faces of which are secured the stop castings A—A. Each of the castings A, as shown, is provided with a rear stop 11, front stop 12, and a central post forming 40 front and rear limiting stops 13 and 14 for the front and rear followers 15 and 16, respectively, of the gear. Interposed between the followers is a cushioning device, that shown in the drawing comprising vertical 45 twin-arranged springs 17—17, said springs being seated at their ends on suitable bosses 18—18 formed on the inner faces of the followers and also held in spaced relation by means of a spring spacer 19. Each of the 50 followers has its ends movable in the recesses provided in the stop castings between the respective main and limiting stops and is further provided with an upward extension 20 and a downward extension 21 in order to 55 form larger bearings for the springs.

The gear proper is operatively connected with the draw bar 22 by means of the improved two-part horizontal yoke. The latter, as shown, comprises two like yoke members 23—23. Each yoke member 23 is of 60 loop form and has side arms 24—24, rear connecting portion 25 and front connecting portion 26. Each of the yoke members is also provided with a pair of side flanges 27—27 adapted to fit over the sides of 65 the draw bar, said side flanges 27 being recessed to accommodate the coupler-key 28, which passes therethrough and also through suitable slots in the draw bar, the stop castings and the draft sills. As 70 clearly shown in Figs. 1 and 2, the side flanges of the yoke members are over-lapped when assembled with the draw bar so that the slots therein will properly align to receive the coupler-key. Furthermore, each of 75 the yoke members 23 is preferably provided with a shoulder or gib 29 to engage the adjacent shoulder on the draw bar butt.

The upper yoke member 23 rides upon the upper flanges 30 of the stop castings and is 80 guided thereby. In order to prevent the upper yoke member from being displaced upwardly, the stop castings are preferably provided with over-hanging flanges 31 at their rear ends to thereby form short grooves or 85 channels within which the rear end of the upper yoke member is confined. The lower yoke member 23 fits against the lower sides of the stop castings and is properly supported by means of the detachable saddle 90 plate 32, the latter having suitable horizontal ledge portions 33 to form guide surfaces for the lower yoke member. The saddle plate 32 also supports the springs and followers, as will be apparent from an inspection 95 of Fig. 3.

By means of the foregoing described construction, I am enabled to employ a two-part horizontal yoke which may be detachably connected with the draw bar and having 100 all the parts so arranged that the gear proper may be taken down without taking out the draw bar. This is accomplished by first removing the saddle plate then taking out the coupler-key and dropping down the lower 105 yoke member, after which the followers and springs can be pulled down from between the stop castings. By the employment of the two-part horizontal yoke, I obtain direct 110 pulls on the rear follower which are sub-

stantially in line with the axis of the springs, thus minimizing any tendency of the rear follower to bend or buckle.

I claim:

5 1. In a draft rigging, the combination with stop members, followers coöperable therewith, cushioning means, a draw bar, of a two-part yoke for operatively connecting the gear proper with the draw bar, each part 10 of said yoke comprising a loop member extending in a horizontal plane and detachably connected to the draw bar, and a saddle plate, the latter being adapted to support the lower yoke part, the upper yoke part 15 being supported by the stop members.

2. In a draft rigging, the combination with draft sills, of stop members secured thereto, followers coöperable with the stop members, cushioning means between the followers, and 20 a draw bar, of a two-yoke arranged to connect the draw bar with the followers and cushioning means, the two-part yoke includ-

ing an upper horizontally extending member, the same being supported by the tops of the stop members.

3. In a draft rigging, the combination with 25 draft sills, of stop members secured thereto, followers coöperable with the stop members, cushioning means between the followers, and a draw bar, of a two-part yoke arranged 30 to connect the draw bar with the followers and cushioning means, the two-part yoke including an upper horizontally extending member, the same being supported by the tops of the stop members, the stop members 35 being provided with flanges over-hanging said upper top member of the yoke to thereby prevent the latter from being displaced upwardly.

In witness that I claim the foregoing I 40 have hereunto subscribed my name this 15th day of Feb. 1917.

GOODRICH Q. LEWIS.
